WIRE DRAWING MECHANISM

Norman H. Nye, Cuyahoga Falls, Ohio, assignor
to The Vaughn Machinery Co., Cuyahoga
Falls, Ohio, a corporation of Ohio

Application May 24, 1940, Serial No. 337,011

7 Claims. (Cl. 205—20)

This invention relates, as indicated, to wire-drawing blocks and the like and more particularly to an improved method and apparatus for cooling such blocks and the wire wrapped thereon.

As wire is drawn through a die, it becomes highly heated and if the wire passes through successive dies without being cooled therebetween, such heating becomes excessive with resultant injury to the wire. This fact has long been recognized by those skilled in the art and various cooling means suggested to overcome the problem. That most generally accepted has been some form of water spray applied to the interior surface of the block or drum thus cooling both the drum and the wire wrapped thereon. Various disadvantages consequent upon the employment of this cooling means soon became apparent, however, such as the tendency of the water to enter the upper bearings supporting the block and the difficulty due to centrifugal force of removing the water from the block in the desired manner and at the desired rate.

It is, therefore, among the objects of this invention to provide an improved method and apparatus for cooling wire-drawing blocks.

Another object is to provide apparatus of the above-described type whereby a cooling liquid such as brine may be circulated within such block without contacting any moving parts and yet be effective to cool both the block and the wire wrapped thereon.

Other objects of this invention will appear as the description proceeds.

To the accomplishment of the foregoing and related ends, said invention, then, consists of the means hereinafter fully described and particularly pointed out in the claims.

The annexed drawings and the following description set forth in detail certain means and one mode of carrying out the invention, such disclosed means and mode illustrating, however, but one of various ways in which the principle of the invention may be used.

In said annexed drawings:

Fig. 1 is an elevational view in cross section of my new block illustrating the cooling means and showing a portion of the driving mechanism;

Fig. 2 is a top view of the non-rotatable inner cooling chamber;

Fig. 3 is a side elevational view of such chamber; and

Fig. 4 is a horizontal cross section taken through the block along the line 4—4 on Fig. 1.

As indicated above, the principle of my invention is adaptable to the various types of wire-drawing blocks, drums and take-up reels commonly employed, whether they be single or double-decked, intermediate on a continuous bench, or the drum on which the wire is wound at the end of the operation. Broadly, the idea of cooling such blocks by means of water or air streams is old as taught by Pat. No. 1,723,313 to Tippet 10 dated August 6, 1929, and Pat. No. 1,959,901 to McIlvried dated March 13, 1934.

Referring now more particularly to the above-described drawings, one preferred embodiment of my invention comprises a cylindrical block or 15 drum 1 about which the wire is wound, mounted on a tubular vertical spindle 2, such spindle being journaled at its lower end in roller bearing 3 and near its upper end in roller bearing 4. Bearing 4 is supported in supplemental frame 5 which in turn rests upon and covers the box-like main frame 6. Said main frame also serves as an oil reservoir in which gear 7, which drives spindle 2, turns. Said main frame is supported by base member 8 which forms a chamber 9 immediately below said spindle.

Mounted at their lower ends in frame piece 10 are two concentrically disposed tubes 11 and 12 which extend upwards through said cored or tubular spindle and support annular chamber 30 13 within the block, tube 11 communicating with the interior of such chamber at one side by way of passage 14 and tube 12 communicating with such chamber on the other side by way of passage 15. For convenience in construction, an 35 opening is provided in the upper end of passage 14 above tube 11, such opening later being tightly sealed as by a screw plug 16, or the like. A plug hole (not shown) is also provided in the top of the block to permit of entrance to the interior thereof. Chamber 13 is provided with a number of baffles 17 to cause a thorough circulation and mixing of a liquid passing therethrough. The exterior surface of said chamber is likewise provided with flow deflecting means in the form of 40 spirally arranged ridges 18 which are designed to enhance the circulation of a cooling liquid contained within said block.

Tube 11 communicates with pressure line 19 by 45 way of valve 20 and discharge tube 12 debouches into inner chamber 21 in frame piece 10 and thence into chamber 9. Also within tubular spindle 2 and mounted in frame piece 10 is an outer concentric tube 22 spaced from tube 12 by 50 perforated ring 23, such means serving to con-

duct any liquid seepage from the interior of the block to outlet 24 and preventing contamination of the oil in main frame 6.

Exterior cooling of the drum and wire wound thereon may be provided in the form of air jets coming from orifices 26 disposed around the inwardly sloping upper face of supplemental frame 5, compressed air being introduced to annular chamber 25 formed by said frame.

The operation of my device may now be described in detail. A cooling liquid, preferably water, is introduced to the interior of the block which is filled to a level just below that of the upper end of spindle 2. A refrigerant, which may also be cold water or other liquid but is preferably brine, for example, from line 19 enters stationary chamber 13 after passing through valve 20, tube 11 and passage 14. It then circulates around baffles 17 to outlet passage 15 and out by way of tube 12 to chamber 9, whence it may be drawn off for re-circulation as in the usual refrigerating system, or otherwise disposed of. As block 1 revolves, the water therein tends to swirl therewith and the spirally arranged ridges 18 on the exterior surface of the inner chamber serve to enhance the circulation of the water within the block, greatly increasing the efficiency with which heat is taken from the block by the water therein, and also the efficiency with which the brine or other refrigerant in the inner chamber extracts the heat from such water.

It is apparent that other means for causing such circulation within the block may be provided as by spiral ridges on the inner surface of such block instead of on the inner chamber and all such means are within the broad scope of the present invention.

It will be seen that the objects of this invention have been achieved in that a means of cooling wire-drawing blocks and the wire thereon has been provided which is most efficient in operation and yet is not endangered by seepage of brine, for example, since such brine nowhere contacts a running seal or joint, nor is the normal operation of the block in any way interfered with.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a wire drawing mechanism, the combination of a hollow rotatable block adapted to contain a cooling liquid against the inner surface of the wire-contacting portion of said block, a non-rotatable inner chamber immersed in such liquid and adapted to have a refrigerating liquid circulated therethrough, and spirally arranged flow deflecting means for enhancing circulation of

such first-named liquid upon rotation of said block.

5 2. In wire drawing mechanism, the combination of a hollow rotatable block adapted to contain a cooling liquid against the inner surface of the wire-contacting portion of said block, a non-rotatable inner chamber immersed in such liquid and adapted to have a refrigerating liquid circulated therethrough, baffle means within said inner chamber, and spirally arranged flow deflecting means on the exterior surface of said chamber for enhancing circulation of such first-named liquid upon rotation of said block.

15 3. In wire drawing mechanism, the combination of a hollow rotatable block adapted to contain a cooling liquid against the inner surface of the wire-contacting portion of said block, a non-rotatable annular inner chamber immersed in such liquid and adapted to have a refrigerating liquid circulated therethrough, baffle means within said inner chamber, a cored spindle fixed in said block and rotatable therewith, inlet and outlet passageways within said spindle communicating with said inner chamber, and spirally arranged ridges on the exterior surface of said chamber for enhancing circulation of such first-named liquid upon rotation of said block.

20 4. In wire drawing mechanism, the combination of a hollow rotatable block adapted to contain a cooling liquid against the inner surface of the wire-contacting portion thereof, an inner chamber within said block sealed from communication with the interior of said block, and means for circulating a refrigerant through said chamber.

25 5. In wire drawing mechanism, the combination of a hollow rotatable block adapted to contain a cooling liquid against the inner surface of the wire-contacting portion thereof, an inner chamber within said block sealed from communication with the interior of said block and adapted to be immersed in such cooling liquid, and means for circulating a refrigerant through said chamber.

30 6. In wire drawing mechanism, the combination of a hollow rotatable block, an inner non-rotatable chamber entirely within said block, a cooling liquid between said chamber and the inner surface of the wire-contacting portion of said block, and means for circulating a refrigerant through said chamber.

35 7. In wire drawing mechanism, the combination of a hollow rotatable block adapted to contain a cooling liquid, a non-rotatable chamber entirely within said block adapted to be immersed in such liquid and adapted to have a refrigerant circulated therethrough, and flow deflecting means for enhancing circulation of such first-named liquid upon rotation of said block.

NORMAN H. NYE.
